(57) **CLAIM**

The ornamental design for a pressure cooker lid, as shown and described.

DESCRIPTION

FIG. 1 is a perspective view of the pressure cooker lid in accordance with the present invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

The elements depicted in broken line in the various figures are included for environmental purposes only, and form no part of the claimed design.
